UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

SHEET-FEEDING MECHANISM.

Application filed May 3, 1924. Serial No. 710,761.

This invention relates to sheet feeding mechanism, and more particularly to sheet grippers.

In some printing presses sheet material must be carried a relatively long distance and accordingly should be quite positively gripped to prevent the sheet material from becoming disengaged or displaced with respect to the grippers. However, when the sheet has reached the position at which it is to be deposited and stripped from the grippers, it is necessary that the stripping be easily done without crimping the sheet material or in anywise adversely affecting the registration of the sheet.

Accordingly, one object of the present invention is to provide sheet feeder gripper mechanism in which the grippers may grip a sheet with a variable pressure so that during the main part of travel of the sheet, the grippers will have a relatively tight hold on the sheet, and at the point of deposit will have a relatively light hold on the sheet.

Another object of my invention is to provide simple, efficient and reliable sheet feeder gripper mechanism adapted to meet the various requirements under service conditions.

These and other objects are accomplished by means of the arrangement disclosed on the accompanying sheet of drawings, in which—

Figure 1 is a fragmentary side elevation, parts being in section, of a printing press embodying my invention, the grippers being in a relatively remote position with respect to the front guide means;

Figure 2 is a similar fragmentary side elevation of the gripper mechanism showing the gripper just at the point where it is about to reach the front guide and the fed sheet is to be stripped from the gripper, and showing means just about to become effective to lessen the hold of the gripper on said sheet; and

Figure 3 is a side elevation of the gripper mechanism on its return movement and showing the gripper with the parts arranged so that its gripping action is at a minimum and preparatory to being reset for a more positive gripping action.

The various novel features of the invention will be apparent from the following description and drawings, and will be particularly pointed out in the appended claims.

Referring to the figures of the drawings, it will be noted that the invention is illustrated in connection with a printing press having an impression cylinder 10 to which sheet material is fed over a feed board 11. The sheet material is temporarily arrested in its movement by front register guides, only one of which, 12, is shown. The sheet material is fed to the front register by grippers and the sheet stripped therefrom when the fed sheet passes into engagement with the front guides.

The gripper herein illustrated includes a relatively stationary jaw 13 secured to an arm 14 mounted on a support 15 and also includes a relatively movable or pivotally mounted gripper jaw 16 which is pivotally mounted at 17 on the arm 14. Normally the movable gripper jaw 16 is held in engagement with the relatively stationary gripper jaw 13 by a spring 18 coiled around a rod 19 which, at its lower end, is pivotally connected at 20 to the rear portion of the movable gripper jaw 16, the spring being compressed between a suitably adjustable abutment 21 on the rod 19 and a latch 22 pivotally mounted upon the arm 14. As shown in Figures 1 and 2, and particularly in Figure 2, the latch 22 is held in an elevated position by a locking member 23 which also is pivotally connected to the arm 14. The locking member 23 is normally held in such position by a spring 24 wrapped around a pin 25 and having one end engaging the upper surface of the arm 14 and the other end engaging the upper wall of the locking member 23. It will be appreciated that if the latch 22 is permitted to swing from its elevated position, shown in Figure 2, to its lower position shown in Figure 3, the spring 18 will be permitted to expand and, accordingly, exert less pressure upon the relatively movable gripper jaw 16 than when the latch 22 is in its elevated position wherein the spring 18 is compressed an increased amount.

As mentioned hereinabove, it is desirable to grip a sheet with a considerable degree of pressure during the main feeding portion of the sheet and to relax said gripping pressure a given amount just about the time when the sheet is to be stripped from the gripper. Accordingly, the latch 22 should be elevated to compress the spring 18 during the greater portion of the feeding movement of the sheet material and the latch 22 should

occupy its lower position to decrease the holding effect of the spring at the point where the sheet is to be stripped from the gripper. As shown in Figure 2, the gripper 5 is firmly holding the sheet 26, the latch 22 being held in its elevated position by the locking member 23. In said figure, however, the gripper has reached a position adjacent the front guide 12 and the locking member 10 23 has reached a position where it is about to be slightly rotated in a clockwise direction by engagement with a roller 27 rigidly supported in a properly supported arm 28. Upon further movement of the gripper toward the front guide 12, the locking member 23 will be rotated in a clockwise direction until the latch 22 is freed from the locking member, whereupon under the tension of the spring 18 the latch 22 will be forced into its 20 lowermost position, and as a result thereof the force with which the sheet is gripped between the gripper jaw will be relaxed so that the sheet may be readily stripped from the gripper jaws as the latter pass forwardly 25 beyond the front guide 12.

Thereafter the gripper is given a return movement as shown in Figure 3 of the drawings, with the latch 22 still in its down position and it continues to occupy that position 30 until the gripper reaches the position shown in Figure 1 wherein the latch 22 again is reset for increasing the compression of the spring for the purpose mentioned. For resetting the latch 22 any suitable abutment 35 29 is provided against which the latch is forced for raising the latter into a position so that the locking member 23 under the influence of spring 24 may move under the latch 22 for releasably holding the latter 40 in its elevated position.

It is my intention to cover all modifications of the invention falling within the spirit and scope of the following claims.

I claim:

45 1. In sheet feeding mechanism, the combination of gripper jaws, and means including a releasably mounted member carried by one of said jaws for automatically varying the gripping force of said same jaws during the operation thereof.

50 2. In sheet feeding mechanism, the combination of gripper members, and means including a releasably mounted member carried by one of said gripper members for automatically varying the gripping force of said same gripper members during the operation thereof.

55 3. In sheet feeding mechanism, the combination of gripper members, and means for automatically varying the gripping force of said same gripper members during a feeding movement thereof and including a spring pressed latch carried by one of said gripper members.

60 4. In sheet feeding mechanism, the combi-

nation of gripper jaws, and means whereby a sheet is yieldably gripped by said jaws with a certain yieldable pressure during part of the cycle of operation and with a different yieldable pressure during another part of 70 said cycle of operation.

5. In sheet feeding mechanism, the combination of a stationary gripper jaw, a movable gripper jaw, a spring operative upon said movable gripper jaw, and means for 75 normally varying the effectiveness of said spring for varying the gripping action of said jaw members during the operation thereof.

6. In sheet feeding mechanism, the combination of a relatively stationary jaw member, a relatively movable jaw member, means for yieldably pressing one against the other for gripping purposes, and means operable upon said last mentioned means for 85 varying the degree of yieldably gripping action.

7. In sheet feeding mechanism, the combination of relatively movable gripper jaws, and means under certain conditions for 90 yieldably pressing said gripper jaws together with a certain degree of pressure and under other conditions for yieldably holding said jaws together with a different degree of pressure.

8. In sheet feeding mechanism, the combination of a relatively stationary gripper jaw, a relatively movable gripper jaw, pressure means operative upon said relatively movable gripper jaw for pressing the latter against the relatively stationary gripper 100 jaw, and a latch by means of which the gripping force between said jaws is varied.

9. In sheet feeding mechanism, the combination of a relatively stationary gripper jaw, a relatively movable gripper jaw, a 105 spring operative upon said relatively movable gripper jaw for creating a gripper force between said jaws, a latch operative upon said spring for varying the gripping force between said jaws, and a releasable 110 locking member operative upon said latch for holding or releasing the latter for varying the effect of said spring.

10. In sheet feeding mechanism for printing presses, the combination of a front guide, relatively stationary and movable gripper members, a spring operative upon said movable gripper member, a latch for compressing the spring a given amount for creating a given gripping force between said 115 gripper members, a releasable locking member for holding said latch in a given position; and means operative upon said locking member for releasing said latch for varying the gripping force of said same gripper members adjacent said guide.

Signed at Chicago, Illinois, this 8th day of April, 1924.

JOSEPH R. BLAINE.
